UNITED STATES PATENT OFFICE

2,262,295

ELECTRIC ANNOUNCING SYSTEM

Walter G. Moore, Pueblo, Colo.

Application December 6, 1938, Serial No. 244,208

1 Claim. (Cl. 200—87)

This invention relates to a service call system and is more particularly designed for use in places such as automobile eating and drinking lots, department stores, etc. where a view from one spot may be had of the entire establishment.

The principal object of the invention is to provide a system and mechanism which can be used to call attention to a particular station when service is desired at that point and which will hold its indication or signal in the operative position until the service is rendered.

Another object of the invention is to provide a call system which will be highly efficient for use in refreshment lots where patrons are served in the automobile; which will show a visible signal for service at each automobile; and which will have a portable operating device which can be attached to the service tray in the automobile.

A further object is to provide a relay box which when the call is received will give a temporary indication at a central station that service is desired and which will maintain a signal at the station location until the service is rendered.

While particularly designed for and exceedingly valuable for use in automobile curb service lots, it will also be found useful in department stores of the type in which all the station locations are located on a single floor where their signals will be visible.

Other objects and advantages reside in the detail construction of the invention, which is designed for simplicity, economy, and efficiency. These will become more apparent from the following description.

In the following detailed description of the invention reference is had to the accompanying drawings which form a part thereof. Like numerals refer to like parts in all views of the drawings and throughout the description.

In the drawings:

Fig. 1 is a perspective view illustrating the invention adapted for use in an automobile food and drink service lot.

Fig. 2 is a cross section through a call box illustrating the operating mechanism.

Fig. 3 is a detail side elevation of the call box in place upon its supporting standard.

Fig. 4 is a detail view of the upper portion of a supporting standard.

Fig. 5 is a circuit diagram for one relay station, the other stations are similar.

The invention employs a series of supporting standards 10 of any desired construction. Each of the standards 10 supports a call box 11 at a

suitable height thereon and at its top supports an electric signal lamp 12.

In an actual installation, the standards 10 also support insulators 13 between which a three wire electric cable 14 is strung. The cable 14 extends to and terminates in a signal box 15 located at a central point or station and which contains an electric bell 16 or other electric audible signal device.

10 A flexible cord 17 of suitable length extends from each call box 11 to a hooked handle member 18 which carries an electric press button 19.

Normally, the member 18 is hooked over a receiving hook 40 on the side of the call box. 15 When in use they are hooked over the door or window of the automobile or the service tray, as shown in Fig. 1, so as to conveniently position the press button 19 within reach of the customer.

20 In each of the call boxes 11 is a relay box 20 containing a first electro-magnet 21 and a second electro-magnet 22. The first electro-magnet actuates a resilient armature bar 23 to close a first pair of contacts 24. The second electro-magnet 22 actuates a pivoted armature bar 25 25 which is pivoted at 26. The armature 25 carries a spring contact arm 27 positioned to close a second pair of contacts 28.

20 The armature 25 is bent to form an offset shoulder 29 which, at the closed position rests upon a projecting shelf 30, to hold the contacts 28 closed. It may be pushed from this shelf by means of a plunger 31 which terminates in a finger button 32 on the exterior of the call box. The plunger 31 is supported at the extremity of 35 a leaf spring 33 which is fixedly secured at its other extremity to the relay box 20, as shown at 34. The extremity of the armature bar 25 is extended downwardly so as to be positioned opposite the extremity of the plunger 31.

40 Current is fed to the entire system from any suitable power source (such as a transformer 35, through a pair of feed wires 36. One of the feed wires 36 leads to the magnet 21 thence to the magnet 22. The other wire 36 is connected to a lead 37 which in turn leads through the flexible cord 17 to the press button 19 thence back to the other terminal of the electro-magnets 22 so that when the press button is operated both magnets will be energized and both armature bars will be attracted.

45 One member of each pair of contacts 24 and 28 is connected to one of the feed wires 36. The other member of the pair 24 is connected by means of a conductor 38 with the audible signal 50 16. The other member of the pair of contacts

28 is connected by means of a conductor 39 with a light signal 12. The other side of the audible signal 16 and the light signal 12 are, of course, connected to the other feed wire 36 to complete the circuit.

Let us assume that the press button 19 is actuated to temporarily close its circuit. The first result of this is to energize the two magnets 21 and 22 so that the armature bars 23 and 25 are lifted. As the bar 25 lifts its shoulder 29 snaps 10 over the projecting shelf 20 so that when the press button is released, the bar 23 will return to its former position but the bar 25 will not return.

The results in a temporary closing of the contacts 24 and a retained closing of the contacts 28. As a result, the signal 18 will give a short indication and the signal light 12 will remain illuminated. The waiter or other attendant will glance along the line of signal lights and note 20 the illuminated light. He will then go to this station to ascertain the patron's desires and will press the plunger button 32. This will push the armature bar 25 from the shelf 20 allowing it to fall and break the contacts 28 to open the 25 circuit to the signal lamp.

For some installations where an elevated signal lamp is not desired or necessary, the lamp

may be incorporated in the relay box as indicated in broken line at A, Fig. 2, and will project its light through a lens in the side of the box as indicated in broken line at B, Fig. 2.

5. While a specific form of the improvement has been described and illustrated herein, it is desired to be understood that the same may be varied, within the scope of the appended claim, without departing from the spirit of the invention.

Having thus described the invention, what is claimed and desired secured by Letters Patent is:

A relay for electric announcing systems comprising: a solenoid; a swinging armature actuated by said solenoid; a resilient contact blade projecting from said armature; an electrical contact positioned in the path of said blade to be contacted thereby when said armature is actuated; a second spring arm projecting from said armature substantially at right angles thereto; an offset portion in said arm; a stationary projection over which said offset portion snaps when the solenoid is energized to maintain the blade in contact with the contact; and a push button positioned so that when depressed it will contact and flex the arm to release the offset portion from said projection when desired.
